DISPLAY PLAQUE

Jerome J. Palumbo, Jr., Evendale, Ohio (Suite 209, Carousel Towers, 8075 Reading Road, Cincinnati, Ohio 45237)

Filed Nov. 8, 1972, Ser. No. 304,608

Term of patent 14 years

Int. Cl. D11—02

U.S. Cl. D29—23 A

FIG. 3

FIG. 2

FIG. 1

FIG. 5

FIG. 7

FIG. 4

FIG. 6

FIG. 1 is a front elevational view of a display plaque showing my new design;

FIG. 2 is a top plan view thereof;

FIG. 3 is an end elevational view thereof;

FIG. 4 is a rear elevational view thereof;

FIG. 5 is a view in section taken on the line 5—5 of FIG. 1;

FIG. 6 is an end elevational view of an opposite end thereof; and

FIG. 7 is a bottom plan view thereof.

I claim:

The ornamental design for a display plaque, as shown.
